UNITED STATES PATENT OFFICE.

CHARLES H. WEITZ, OF PIEDMONT, CALIFORNIA.

WATERPROOFING INSERTION MEMBER.

Application filed July 23, 1927. Serial No. 207,896.

The invention forming the subject matter of this application relates to waterproofing insertion members, that are to be disposed between the boarding of a building frame and the plaster stucco thereon, in order to prevent any leakage from the outside to the inside between the adjoining members of said building frame.

In the present practice after the building structure has been framed and boarded in, the boarding is covered with waterproof paper before the plaster stucco is applied thereon. The members of the framing, including the jambs, usually shrink, thereby creating more or less of a clearance between the joints of the adjoining frame members. The water leaks through the said clearance and thereby causes damage to the walls of the interior compartments of the building.

An object of the present invention is to provide a waterproofing insertion member to cover up the joints of the window or door jamb or other building elements, in such a manner as to offer an increased resistance 25 against the leakage of water past the joints thereof.

Another object of the invention is the provision of a waterproofing insertion member which may be permanently secured to the jamb structure, thereby obviating any danger 30 of an uncovered clearance when the jamb tends to shrink away from the other frame members. The said insertion member to be made of strong, but pliable waterproof material so as to completely cover the joints about the jambs and adjoining parts regardless of the shape or unevenness thereof.

A further object of the invention is to provide a waterproofing insertion member, 40 which also functions as a stop limit to indicate the level of the exterior plaster stucco and thickness thereof.

Other and ancillary objects of my invention will be suggested in the following 45 description and in the use of the device of my invention. Certain of the objects, or certain portions or combinations of the objects of my invention may be attained with the use of less than all its advantageous features, or with modifications within its purview. It is petitioned therefore, that my invention be limited only by the claims constituting its final determination.

In the accompanying drawings forming 55 part of this specification:

Figure 1 is a transverse section of the waterproofing insertion member per se; and Fig. 2 is a fragmentary plan of the same.

Fig. 3 is a horizontal sectional view of a building frame portion adjacent to the jamb 60 of a window or door and showing one form of use of my device.

Referring to the drawings, my device involves two main elements: a pliable waterproof strip 1 and a clip member 2.

The long strip 1 is made of a waterproof material, such as light canvas treated with asphaltic material, and which is substantially stronger than the paper used for sheathing covering.

The clip member 2 is made of sheet metal, the length of which being equal the length of the strip 1. The clip is bent parallel to the longitudinal axis thereof so that it forms a reenforcing rib 3 and a stucco bearing and receiving portion 4.

In Fig. 3 the structure of the framing is illustrated as comprising wood sheathing 5, a stud 6 and an inside plastered wall 7. A jamb 8, is secured to the stud 6 and forms a 80 portion of the reveal 9 of a window opening, for example.

In the use of my invention, the strip 1 is placed around the outside corner of the wood sheathing 5 adjacent the stud 6, and the clip 85 2 is firmly secured in the stud-jamb corner 10 by means of nails 11 so that all joints about the opening are covered.

The width of the clip 2 is approximately one inch, the usual thickness of plaster stucco 90 on the exterior of frame building walls; therefore the outside face 12 of the clip is a stop limit and is adapted to indicate the level of the stucco thereat and also the thickness.

After the clip is secured to the jamb 8, the pliable strip 1 is folded around the corner of the wood sheathing so that the whole reveal is protected thereby. The free edge of the strip is secured to the wood sheathing at a 100 distance from the reveal by any means, such as the nails 13'. The wood sheathing is then covered by a sheet of the customary waterproof paper 13, the edge of said paper overlapping the free end of the strip 1.

The plaster stucco 14 is applied lastly. In the present practice the plastering in the reveal 9 is uneven, because no means are provided to gauge the correct thickness of the plaster stucco thereat or to limit the 110

level of the plaster surface. The clip 2 clearly indicates to the plaster the level of the stucco surface by means of the rebent stop limit 3. The surface of the plaster 5 stucco and the stop limit 3 may be coated or painted with a finishing coat simultaneously, thereby producing an even and uniform surface in the reveal 9.

The double function of the clip 2 is apparent from the aforesaid description, as the 10 said clip secures the strip 1 to the jamb 8 and simultaneously forms a stop limit to indicate the thickness of the plaster stucco and the finishing surface thereof. The strip, it 15 is to be noted, is crimped in the clip 2, and the unit is fixedly secured to the jamb, therefore it will always cover the joints of the adjoining parts regardless of the shrinkage 20 thereof. As stated, the strip is made of waterproof cloth or paper sufficiently strong to withstand the pull exerted thereon by the shrinkage or limited relative movement of the adjoining parts of the frame and to resist any high wind pressure tending to force water 25 therethrough.

The waterproof insertion member heretofore described may be used at any corner or part of a building frame where it is necessary to provide particular protection against 30 moisture creepage therewith.

In manufacturing the device, while the various elements thereof may be constructed in any suitable manner and of any suitable materials, yet it is preferable to form the 35 same of waterproof cloth and from sheet metal stampings on account of the cheapness, lightness and strength thereof.

From the foregoing description taken in connection with the accompanying drawings, 40 the advantages of the construction and the method of operation will be readily understood by those skilled in the art to which the invention appertains, and while I have described the principle of operation, together with the device which I now consider 45 to be the best embodiment thereof, I desire to have it understood that the device shown is merely illustrative and that such changes may be made, when desired, as fall within 50 the scope of the appended claims.

Having thus described my invention, I claim as new and desire to secure by Letters

Patent of the United States, the following:

1. A waterproofing insertion member for covering the adjoining edges of a building frame structure comprising, a pliable and waterproof strip and a clip in combination therewith to secure an edge of said strip to one of said adjoining frame members. 55

2. A waterproofing insertion member for covering the adjoining edges of a building frame structure comprising, a pliable and waterproof strip, a clip in combination therewith to secure an edge of said strip to one of said adjoining members, and means on said 60 clip to determine the limiting thickness of the wall covering to be disposed upon said strip. 65

3. A waterproofing insertion member for preventing leakage between the joints of adjoining building frame members comprising, a pliable and waterproof strip and a clip in combination therewith and being adapted to be secured to one of said frame members; said clip comprising a bearing portion, and 70 a rib portion to cooperate with said bearing portion to form a receptacle for the wall-covering material and to determine the outside surface limit of said wall covering. 75

4. A waterproofing insertion member for building frame structures comprising a pliable waterproof strip and a clip; said clip comprising a bearing portion, a bent portion forming an angle with said bearing portion, a rebent portion cooperating with said bent 80 portion for crimping said strip therebetween, and means to secure said clip to a member of the building frame. 85

5. A waterproofing insertion member for building frame structures comprising a pliable waterproof strip and a clip; said clip comprising a bearing portion, a bent portion forming an angle with said bearing portion, a rebent portion cooperating with said bent portion for crimping said strip therebetween, and means to secure said clip to a member of the building frame, said rebent portion being a stop limit to determine the 90 surface level and thickness of the wall material to be disposed upon said strip and 95 clip. 100

In testimony whereof, I affix my signature.

CHARLES H. WEITZ.
